United States Patent Office

Des. 218,082
Patented July 14, 1970

218,082

REFRIGERATED BEVERAGE DISPENSER OR SIMILAR ARTICLE

Richard T. Cornelius, Minneapolis, Clark L. Lofgren, Golden Valley, and James R. Reichow, Edina, Minn.,
assignors to The Cornelius Company, Anoka, Minn.,
a corporation of Minnesota

Filed Dec. 3, 1968, Ser. No. 14,769

Term of patent 14 years

Int. Cl. D15—12

U.S. Cl. D94—3

FIG. 1 is a perspective view showing the front and one side of a refrigerated beverage dispenser showing our new design, the opposite side having substantially the same appearance.

FIG. 2 is a perspective view showing the rear and said one side thereof.

FIG. 3 is a top view thereof.

We claim:

The ornamental design for a refrigerated beverage dispenser or similar article, substantially as shown and described.
